UNITED STATES PATENT OFFICE.

ROBERT SNEIDER, OF BROOKLYN, NEW YORK.

DESIGN FOR AN ENVELOPE.

SPECIFICATION forming part of Design No. 14,993, dated May 6, 1884.

Application filed January 11, 1884. Term of patent 14 years.

To all whom it may concern:

Be it known that I, ROBERT SNEIDER, a resident of Brooklyn, Kings county, State of New York, have invented a new and original 5 Design for Envelopes, of which the following specification is a full, clear, and exact description, reference being had to the accompanying drawing, forming part of this specification.

The drawing represents a face view of an 10 envelope provided with my design.

This invention relates to a design for an envelope or other similar article.

The letter A represents an envelope, a be-

ing the face, and b the flap. The flap b is shorter and narrower than face a, and the 15 corners c are shown to be beveled. From the side edge, d, projects fringe or lace e, and from the lower edge, g, projects fringe or lace f.

I claim as my invention—

The design for an envelope having flap b 20 shorter than face a, and provided with fringe or lace f, as described and shown.

ROBERT SNEIDER.
